UNITED STATES PATENT OFFICE

MITCHELL S. BUCK, OF PHILADELPHIA, PENNSYLVANIA

VALVE

Application filed December 21, 1928. Serial No. 327,678.

This invention relates to valves adapted to be used in the connections between the supply pipes and radiators of heating systems but obviously may be used in many other relations where it is necessary to more or less frequently repack the valves against leakages of the heating fluid therethrough.

The main object is to associate the packing elements with the valve operating stem and valve in such manner that the valve may be closed to prevent the entrance of the heating fluid to the packing glands preceding the removal of the packing elements and valve operating stem thus permitting the packing parts to be easily and expeditiously renewed when necessary or desirable without disconnecting the valve from the radiator or supply pipe.

Another object is to permit a packing element to be removed and replaced at will without removing the valve operating stem.

A further object is to permit a valve operating stem and all of the packing elements to be removed when the valve is closed without disturbing said valve from its closed position.

Other objects and uses relating to specific parts of the device will be brought out in the following description.

In the drawings:

Figure 1 is a top plan of a valve embodying the various features of my invention.

Figure 2 is a sectional view taken in the plane of line 2-2, Figure 1.

Figure 3 is an elevation of the detached valve operating stem with one of the packing members thereon.

In order that the invention may be clearly understood I have shown a radiator valve case —1— provided with a valve chamber —2— and a valve seat —3— surrounding the inlet —4— for the heating fluid, said valve being provided with suitable means as the nipple —5— for connection with the radiator or other heat distributing apparatus.

The passage of the heating agent into the chamber —2— is controlled by a valve —6— of less diameter than the chamber and adapted when closed to firmly engage the seat —3— and thereby to cut off the passage of the heat-

ing agent from the part —4— through the outlet nipple —5—.

The top of the valve case —1— is provided with a central opening —7— coaxial with the part —4— and some distance above the valve seat —3—, said opening being of sufficient diameter to permit the passage of the valve —6— therethrough by vertical displacement, when necessary.

The walls of the opening —7— are threaded to receive a hollow bushing —8— which is threaded externally and adapted to be screwed into the opening —7—, the upper end of said bushing being enlarged to form an annular flange —9— for engaging the upper end face of the valve case when the bushing is tightly screwed in place.

The outer end of the bushing is flat and its lower end is somewhat conical or tapered downwardly and is provided with an opening —10— coaxial with the passage —4— and opening —7—, the walls of said opening being threaded for receiving an externally threaded stem —11— projecting upwardly from the valve —6— so that when the threaded stem —11— is rotated in one direction it will close the valve —6— against the seat —3— and when rotated in the opposite direction will open the valve from the seat.

The valve stem —11— is formed with a central vertical socket —12— extending from the upper face of the valve —6— through the upper end of the valve stem and preferably square or angular in cross section for receiving a correspondingly square or angular lower end —13— of a valve operating stem —14— presently described.

The bushing —8— is provided in its upper side with a socket —15— extending downwardly from the upper face thereof for receiving the packing forming a part of the subject matter of the invention, said socket being coaxial with the valve stem 11 and having its peripheral walls threaded and adapted to be engaged by an externally threaded lower —16—. The bottom wall of the socket —15— is provided with a central reduced opening 17 for receiving a cylindrical portion of the valve stem.

The adjacent portion of the valve stem 14

100

extends from the socket 12 in the valve stem 11 upwardly through the opening 17 and through a corresponding central opening 18 in the follower 16.

- 5 The portion of the valve operating stem 14 within the socket 15 is provided with an annular flange —19— and between this flange and the bottom wall of the socket —15— is placed a packing member —20— closely fitting within the peripheral walls of the socket —15— and against the adjacent portion of the valve operating member —14—.

The follower —16— is provided in its lower side with a socket —21— of about the same diameter as the flange —19— for receiving said flange and an additional packing member —22—, the latter being disposed between the upper face of the flange —19— and top wall of the socket —21—.

- 20 The upper end of the follower —16— is provided with opposite flat faces —16'— adapted to be engaged by a wrench or equivalent tool for tightening and releasing said follower in the socket —15—, it being understood that the follower is free to turn independently of the valve operating stem —14—.

The portions of the valve operating stem —14— immediately above and below the annular flange —19— are cylindrical and these 30 cylindrical portions are engaged in corresponding cylindrical openings in the bottom wall of the socket —15— and top wall of the socket —21— thereby permitting turning movement of the valve operating stem —14— relatively to the bushing —8— and follower —16— for effecting a corresponding turning movement of the screw-threaded valve stem 11 for opening and closing the valve 6.

- 40 The upper end of the valve stem 14 above the annular flange 19 extends some distance above the follower 16 and this extension as 23 is preferably square or angular in cross section for receiving a handle 24 by which the valve operating stem may be rotated for 45 opening and closing the valve 6, the handle 24 being shown by dotted lines in Figure 2.

It is evident, however, that any other suitable means may be employed for rotating the valve operating stem.

- 50 The bushing —8— is provided with a chamber —8'— between the bottom wall of the socket —15— and upper internally threaded end of the bushing for receiving the upper end of the threaded extension or 55 stem 11 of the valve 6 as the latter is raised and lowered by turning movement through the medium of the operating stem 14, the lower end of the bushing 8 being spaced a sufficient distance above the valve seat 3 to 60 allow for the opening and closing of the valve 6.

It is now evident that when the valve 6 is closed against the seat 3 communication between the inlet 4 for the heating fluid and

tween the inlet and outlet of the valve case will be cut off thus permitting the removal of the entire packing device for repairs or adjustments when desired without liability of the escape of the heating fluid through the valve case and also without disturbing the connections of the valve case with the supply pipe and radiator or other parts of the distributing system.

70

75

Operation

When the valve case is connected in the heat-distributing system and the valve and packing device are installed in operative position the valve may be opened and closed 80 at will by simply turning the valve operating stem 14 in reverse directions through the medium of the handle 24 or other suitable operating member.

When the valve is opened the threaded 85 engagement of the valve stem 11 with the internally threaded lower end of the bushing 8 prevents the escape of the heating fluid past the threaded joints but in case there should be any slight leakage at this joint 90 it would be immediately checked by the packings 20 and 22 of the packing device.

On the other hand, if it should become necessary to replace the packings 20 and 22 the valve stem 14 will be operated to firmly 95 close the valve 6 whereupon the follower 16 would be removed from the socket 15 to permit the removal of the packing member 22 and if necessary, the valve operating stem 14 could then be removed to permit the removal 100 and renewal of the packing 20, these operations being performed without liability of leakage of the heating fluid through the opening 17 in the bushing 8.

In assembling the various parts of the 105 packing device in operative position, the packing member 20 is first placed in the bottom of the socket 15 after which the valve operating stem 14 is placed in operative position with its lower end in sliding engagement with the walls of the socket 12 of the valve stem 11 and the annular flange 19 in engagement with the upper face of the packing 20.

The packing member 22 is then placed over 110 and upon the upper face of the flange 19 after which the follower 16 is screwed tightly in place in the socket 15 to firmly clamp the packing 20 against the bottom wall of said socket and at the same time to firmly clamp 115 the packing 22 against the upper face of the flange 19 without interfering with the free turning movement of the valve operating stem 14.

When the parts of the packing device have 120 been restored in the manner just described, the valve operating stem 14 may be turned in the proper direction for opening the valve 6 and allowing the heating fluid to pass from the inlet 4 into the outlet 15 and thence into 125 130

15 valve chamber and also communication be-

the radiator or other heating distributing system.

When the bushing —8— is secured in operative position in the valve case —1— it becomes a part of said valve case for practical purposes and is only made separate therefrom to permit the removal of the valve —6— through the opening —7— when the bushing is removed.

What I claim is:

- 10 The combination with a valve case having a valve chamber therein with an inlet and an outlet for said chamber and a valve seat in said chamber, a valve member movable into and out of engagement with said seat and having a hollow externally threaded extension, a bushing threaded into one end of the case and having the outer end thereof flat and provided with an enlarged flange for engaging the end face of said case, said bushing including a socket in its outer flange end and a hollow extension in said casing having a threaded opening therein in screw engagement with said valve extension for maintaining the valve in and out of engagement with
- 15 said seat, said socket having a reduced opening through the bottom wall thereof, a valve-operating stem extending through said socket and opening and having splined connection with said hollow extension of the valve
- 20 for turning the latter to open and close the valve as the stem is rotated, and means in said socket and engaging said bushing for holding the valve-operating stem against end-wise movement.
- 25
- 30
- 35 In witness whereof I have hereunto set my hand this 17th day of December, 1928.

MITCHELL S. BUCK.
